UNITED STATES PATENT OFFICE.

FRANK R. LAY, OF GREENFIELD, INDIANA, ASSIGNOR OF ONE-HALF TO
WALTER W. MCCOLE, OF GREENFIELD, INDIANA.

SIGHT-INDICATOR FOR TELEPHONES.

No. 820,213.

Specification of Letters Patent.

Patented May 8, 1906.

Application filed April 22, 1905. Serial No. 256,882.

To all whom it may concern:

Be it known that I, FRANK R. LAY, of Greenfield, county of Hancock, and State of Indiana, have invented a certain new and useful 5 Sight-Indicator for Telephones; and I do hereby declare that the following is a full, clear, and exact description thereof, reference being had to the accompanying drawings, in which like numerals refer to like parts.

10 The object of this invention is to indicate by sight whether or not a telephone has been rung and when there is a plurality of telephones in an office to indicate which one was rung. It is therefore in the nature of an attachment to a telephone without changing the telephone and can be used in connection with any telephone.

15 The effect of the invention is to show whether or not a telephone has been rung in one's absence and which of two telephones was rung, and thereby avoiding the confusion resulting from inability to distinguish from the bells of the telephones which telephone rang. It saves time and annoyance both to the central station and to the local user of calling up the wrong telephone in answer to a ring.

20 The general nature of the invention will be understood from the accompanying drawings and the following description and claims.

25 In the drawings, Figure 1 is an elevation of the device in connection with two telephones, one of the telephone-cases being broken away. Fig. 2 is a central vertical transverse section 30 through the sight-indicator. Fig. 3 is a front elevation of the same. Fig. 4 is an inside elevation of the front plate of the device separated and turned around and a front elevation of the upper part of the casing with 35 the front plate removed therefrom and the wiring between the two parts, the casing being partly broken away.

40 In detail the drawings show a wall-telephone 10 and a portable desk-telephone 12 and a sight-indicator 14. The sight-indicator consists of a casing 15, shown here substantially semicircular in elevation with the flat side on the bottom, so that it can readily rest upon a desk or table. The front side of 45 the casing is closed by a removable plate 16, secured by screws 17. On the inside of the front plate are two magnets 18, with a core 19 extending into both magnets and longitudinally movable alternately by said magnets, as

they may be alternately energized. Said core 55 has pivotally connected to it a pendulum-like rod 20, pivoted at its upper end to the post 21, which is secured to the front plate 16. The lower end of the rod has its end turned horizontally at 22 and extends loosely into a 60 slot 23 in an oscillating plate 24, pivoted centrally on the post 25. The plate 24 is slotted at both ends, and in the slot in the upper end a crank-shaft end 26 of the crank of the shaft 27 is mounted, which extends through the 65 front plate 16 and carries an indicating-finger 28.

Upon the casing 10 there are binding-posts 30, 31, 32, and 33. The wire 34 runs from one magnet 18 to the post 31. Another wire 70 35 runs from the post 30 to the base of the post 21 on the plate 18 and the current passes from the wire 25 through the plate 16, through a lead-wire 36 to the magnet. The wire 35 may, if desired, run directly to the magnet. 75 The wire 37 runs from the post 32 to the other magnet 18 and the wire 38 from said magnet to the post 33.

The wall-telephone 10, which may be called the "new" telephone, has its bell-circuit connected with the binding-posts 30 and 31 through the wires 50 and 51. The desk-telephone 12, which may be called the "old" telephone, is connected with the binding-posts 32 and 33 by the wires 52 and 53. Therefore each telephone has a separate electrical connection with its particular magnet 18, and when a telephone is rung its particular magnet is energized and the core 19 moved toward said magnet and thus the finger 28 85 changed from the full-line position (shown in Fig. 3) to the dotted-line position or the reverse. The changed position of the parts is also indicated by dotted lines in Fig. 4. Therefore when the old telephone is rung 90 the core 19 will be moved into the position shown in Fig. 4 and the finger 28 point to the word "Old" on the face-plate 16. If, however, the new telephone is to be rung, the core 19 would be thrown from its position in Fig. 4 to the left and the associated parts into the dotted-line positions and the finger 28 into the dotted-line position (shown in Fig. 3) and pointing to the word "New." If the new telephone be rung a second time, the finger 100 95 will not be changed in its position.

In order to operate satisfactorily, the winding in the magnets of the bell or sound-

indicator and the magnets of the sight-indicator must have substantially the same number of ohms in order to prevent one of the indicator-circuits being cut out by the current short-circuiting, or rather pursuing the course of least resistance. The number of ohms need not be identical, but must be substantially the same in the windings of the two indicators.

10 I do not wish to be limited to the details of the construction shown nor to any particular form of magnet or other electrical apparatus capable of performing the work of the magnet shown in such situation and is a known substitute therefor. A helix-magnet has been used; but there are other well-known electrical equivalents which may be used in place of a helix-magnet.

15 What I claim as my invention, and desire to secure by Letters Patent, is—

20 1. The combination with a plurality of telephones having bell-circuits, of a sight-indicator, electrical means for controlling said sight-indicator, and electrical connection 25 with the bell-circuits for indicating the telephone over which a call has been made.

25 2. The combination with a plurality of telephones, of a sight-indicator with a pair of oppositely-located magnets, separate electrical connection between the bell-circuit of

each telephone and one of said magnets, a core for the two magnets, an indicator-finger, and means actuated by the movement of said core for moving said finger.

3. The combination with two telephones, 35 of a sight-indicator with a pair of oppositely-located magnets, an electrical connection between the bell-circuit of each telephone and one of said magnets, a core for said magnets, an oscillatory plate mounted near said core, 40 an arm connected with said core adapted to oscillate said plate when the core is moved by a magnet, a crank-shaft operated by said plate, and an indicator-finger secured on said crank-shaft.

45

4. The combination with two telephones, of a sight-indicator having a face-plate with a symbol representing each telephone, a finger adapted to point to one or the other of said symbols, and electrical means in said indicator for actuating said finger, said electrical means being connected with said telephones.

50

55 In witness whereof I have hereunto affixed my signature in the presence of the witnesses herein named.

FRANK R. LAY.
